CLAIM

I claim the ornamental design for a light emitting diode, as shown now described.

DESCRIPTION

FIG. 1 is a front view of a light emitting diode showing a first embodiment of my new design, the rear view being identical to the front view;

FIG. 2 is a top plan view of the first embodiment;

FIG. 3 is a right side view of the first embodiment, the left side view being identical to the right side view;

FIG. 4 is a bottom view of the first embodiment;

FIG. 5 is a sectional view of the first embodiment taken along lines 5—5 in FIG. 2; and

FIG. 6 is a perspective view of the first embodiment.

FIG. 7 is a front view of a light emitting diode showing a second embodiment of my new design, the rear view being identical to the front view;

FIG. 8 is a top plan view of the second embodiment;

FIG. 9 is a right side view of the second embodiment, the left side view being identical to the right side view;

FIG. 10 is a bottom view of the second embodiment;

FIG. 11 is a sectional view of the second embodiment taken along lines 11—11 in FIG. 8; and,

FIG. 12 is a perspective view of the second embodiment.
